(57) **CLAIM**

The ornamental design for a personal carrying case for electronic vaping devices, as shown and described.

DESCRIPTION

FIG. 1 is a top perspective view of an embodiment of a personal carrying case for electronic vaping devices of the present application;

FIG. 2 is a first side plan view of the embodiment of FIG. 1;

FIG. 3 is a second side plan view of the embodiment of FIG. 1;

FIG. 4 is a front plan view of the embodiment of FIG. 1; FIG. 5 is a top perspective view of another embodiment thereof;

FIG. 6 is a first side plan view of the embodiment of FIG. 5;

FIG. 7 is a second side plan view of the embodiment of FIG. 5; and,

FIG. 8 is a front plan view of the embodiment of FIG. 5. The broken lines in the drawings depict parts of the personal carrying case for electronic vaping devices that form no part of the claimed design.

1 Claim, 6 Drawing Sheets
